UNITED STATES PATENT OFFICE.

NICHOLAS R. HOMYER, JR., OF GRANITE CITY, ILLINOIS.

TICKET-HOLDER.

1,217,177.

Specification of Letters Patent. Patented Feb. 27, 1917.

Application filed April 1, 1916. Serial No. 88,415.

To all whom it may concern:

Be it known that I, NICHOLAS R. HOMYER, Jr., citizen of the United States, and resident of Granite City, Madison county, and 5 State of Illinois, have invented certain new and useful Improvements in Ticket-Holders, of which the following is a specification containing a full, clear, and exact description, reference being had to the accompanying drawings, forming a part hereof.

My invention relates to an improved ticket-holder for the use of conductors and others, and it is especially adapted for handling children's tickets upon street cars, al- 15 though it may of course be used by the conductors of many other forms of vehicles, such as public automobiles.

The object of my invention is to provide an improved ticket-holder which shall be 20 fitted with means for conveniently attaching it to the conductor's belt or pocket, and also be supplied with improved mechanism for holding a reasonable supply of tickets in readiness to be quickly detached and delivered consecutively, without interfering with the conductor's regular duties.

My invention consists in the novel construction and arrangement of parts herein- 30 after described and specifically designated in the appended claims.

In the drawings,

Figure 1 is a perspective view of my street-car ticket holder.

Fig. 2 is a vertical section of the same, 35 and

Fig. 3 is a horizontal section, taken on the line 3—3 of Fig. 2.

The numeral 1 indicates a rectangular box, preferably made of sheet-metal and 40 nickel-plated, and having on one side a suitable lid or door 2, which is secured to said box by means of hinges 3 and a clasp 4.

The top of said box is provided with a delivery-slot or opening 5, into which the conductor inserts his finger or thumb in removing the tickets one at a time. The wall of said box 2, at the delivery-end of 45 said slot 5, is cut away just the thickness of one ticket, so that but a single ticket can be slid out at a time; the said upper end of said wall at that point forming a stop, or barrier, for the delivery-ends of all of the tickets except the top one of the lot.

The bottom of said box 1 is closed, and 50 two spring-holders 6 cylindrical in form, are fixed at their lower ends on said bottom.

Telescopically mounted within the said fixed spring-holders 6 are the sliding cylindrical spring-guides 7, the upper ends of which are fixed to the undersurface of a 60 ticket-follower 8.

Mounted within the said spring-holders 6 and extending from the bottom of the box upwardly into the said cylindrical spring-guides 7, are coil-springs 9 and 10. 65

The upper ends of the said springs 9 and 10 engage the under surface of the said spring guide 7 and normally urge said follower upwardly.

The numeral 11 indicates a small handle, 70 which is fixed upon and depends from the underside of the said follower 8 in the space between said parallel spring-guides 7, for a purpose hereinafter mentioned.

A suitable hook 12 has its lower end 75 loosely secured to an eye 13 fixed upon the upper surface of the box-bottom, so that said hook may engage the said handle and hold the said follower 8 in a retracted position while the tickets are being placed 80 within the ticket-holder.

The numeral 13^a indicates a supply of tickets, which are made of card-board in the usual manner and placed in the space between the slotted top of said box 1 and 85 the said follower 8 so they will be urged upwardly toward said slot 5 by the said springs 9 and 10 pressing against the said follower.

Suitable guides 14 are provided for the 90 said follower.

The numeral 15 indicates the usual wire clamping-device for engaging the conductor's belt or pocket, to secure the ticket-holder to said belt or pocket in a position 95 convenient to the conductor's hand, during use of the device.

The ticket-holder, as above described, may be made of any desired size, to hold 100 a large or small number of tickets.

The operation of my invention should be obvious, and I will not describe its function in detail, except to say that in "filling" the ticket-holder the operator grasps the said handle 11 and retracts the said follower 105 8 against the power of the said springs 9 and 10, and moves said follower downwardly until said handle reaches the plane of the upper end of said hook 12, when the latter is made to engage said handle and thereby hold the said follower retracted during the operation of placing a 110

supply of tickets in the holder, after which said follower is released by detaching said hook from said handle.

The said follower presses the uppermost 5 ticket against the underside of the slotted top of said box 1, where it can be readily slid out of said slot by the frictional contact of the conductor's finger or thumb; and in a like manner all of said tickets 13^a may 10 be consecutively delivered without delay or inconvenience on the part of the conductor.

The spring 10 is preferably made heavier than the spring 9, so as to exert more force 15 near the delivery-end of said slot 5, where the greater force is necessary in supporting the tickets against the pressure of the conductor's finger while detaching a ticket.

I claim:

1. An improved ticket-holder for conductors' use, comprising a box or closure, 20 a lid for same, suitable fastenings for said lid, there being a ticket delivery-opening in said box having a stop to permit the passage of but one ticket at a time therefrom, 25 two parallel spring-holders fixed at their lower ends on the bottom of said box, a ticket-follower, two parallel spring-guides

having their upper ends fixed to the said ticket-follower and their lower ends telescopically engaging within said spring-holders, springs mounted in said spring-guides and spring-holders, for moving said follower, one of said springs being nearer to said delivery-opening and made heavier than the remaining spring, and means for 35 holding said follower in a retracted position in opposition to the power of said springs in filling the ticket-holder with tickets.

2. A ticket-holder having a ticket-follower, two parallel spring-guides on said follower, springs in said spring-guides, a handle on said follower in the space between said spring-guides, and a hook for engaging 40 said handle, to retain said follower retracted while filling the holder with tickets. 45

In testimony whereof, I have signed my name to this specification, in presence of two subscribing witnesses.

NICHOLAS R. HOMYER, JR.
